UNITED STATES PATENT OFFICE

OTTO H. HARTMANN, OF CASSEL-WILHELMSHOHE, GERMANY, ASSIGNOR TO SCHMIDT'SCHE HEISSDAMPF-GESELLSCHAFT M. B. H., OF CASSEL-WILHELMSHOHE, GERMANY, A CORPORATION OF GERMANY

HIGH-PRESSURE LOCOMOTIVE

Application filed October 27, 1928, Serial No. 315,558, and in Germany June 15, 1928.

In two-pressure locomotives in which a considerable part of the total steam is generated in the low-pressure boiler, interstage superheating can be conveniently effected 5 by mixing the exhaust from the high-pressure stage of the engine with superheated low-pressure steam.

If, however, the high-pressure locomotive is so constructed that the steam needed to 10 develop the power of the engine is generated almost entirely in the high-pressure boiler while the smoke-tube boiler serves principally as a feed-water heater and at most generates only a small fraction of the 15 total steam, considerable difficulties are experienced in connection with the interstage superheating.

Such difficulties, moreover, cannot be overcome by the application of a superheater 20 disposed in the flue gases, the simple construction of which renders it in other respects desirable, because in such a superheater the oil contained in the exhaust steam would burn on to the tubes.

On the other hand, superheating by saturated steam from the high-pressure boiler does not meet the requirements of the case, because the required high degree of superheat cannot be attained.

Such a temperature can be reached, however, if the high-pressure steam is highly superheated before its application as heating steam in the interstage superheater, but it is difficult to arrange superheaters in the 35 limited space available in the locomotive so that the necessary heat can be imparted to the high-pressure steam before admission to the interstage superheater and again after leaving the latter and before admission to 40 the high-pressure stage of the engine.

The object of the present invention is to provide a solution of the above problem for a high-pressure locomotive with a smoke-tube feed-water heater serving in some cases 45 for the generation of low-pressure steam, the heater lying in the flue of the high-pressure boiler containing or constituting the fire box.

According to the present invention, the 50 exhaust steam from the high-pressure stage

of the engine, in some cases in conjunction with the low-pressure steam generated in the smoke-tube feed-water heater, is highly superheated in an interstage superheater by means of superheated high-pressure steam 55 from a superheater which lies wholly or in part in a flue leading from the high-pressure fire box to the smoke-tube feed-water heater.

In order to avoid burning the superheater 60 tubes, specially with high rates of fuel consumption per unit area of the grate, a certain number of the water tubes of the high-pressure boiler are so arranged in the flue that the products of combustion from the 65 furnace must pass between them before reaching the superheater.

According to a preferred form of the invention, in addition to the superheater for the high-pressure steam going to the interstage superheater, a second superheater is 70 arranged in the flue leading from the high-pressure fire box to the smoke-tube feed-water heater, in which second superheater the high-pressure steam coming from the 75 interstage superheater is again highly superheated before admission to the high-pressure stage of the engine.

According to another form of the invention, the two superheaters above mentioned 80 are so arranged that they extend through the smoke tubes of the feed-water heater with a considerable part of their length in the flue leading from the high-pressure fire box to the smoke-tube feed-water heater. 85

Referring to the accompanying drawings:

Figure 1 shows a longitudinal section through a locomotive fitted with one constructional form of the new arrangement of 90 interstage reheating;

Figure 2 is a section on the line II—II of Figure 1;

Figure 3 is a cross-section on the broken line III—III of Figure 1; while

Figure 4 shows a longitudinal section of the locomotive with a modified arrangement of the interstage superheating.

For the present invention it is immaterial whether the high-pressure steam is gener- 100

ated by direct or indirect heating; in the illustrative forms shown in the drawings, the steam-and-water drum of the high-pressure boiler is heated according to the indirect method.

5 In the form of the invention shown in Figures 1 to 3, the water-tube fire box, A, and the smoke-tube boiler, B, are connected by a flue, C.

10 The water tubes, 1, of the fire box are connected at their lower ends to water headers, 2, and at their upper ends to intermediate headers, 3, the steam from the latter passing into the heating elements which lie in the 15 high-pressure boiler drum, 4, while the condensate formed in the heating elements is led back through downcomers into the lower water headers, 2. This kind of indirect steam generation by means of a heat carrier 20 circulating in a closed tube system is well known and does not therefore require further description here.

To the intermediate headers, 3, water tubes, 5, serving as walls for the flue, C, are 25 also connected, the lower ends of these tubes being connected to a water header, 6. Besides the tubes, 5, serving as walls for the flue, other water tubes, 8, are provided which likewise extend from the header, 6, to the 30 intermediate headers and are so formed that they are distributed over the cross-section of the flue, C.

In Figure 2 are shown the heating elements, 9, lying in the high-pressure drum, 35 the steam pipes, 10, leading from the intermediate headers, 3, to the heating elements, 9, and the condensate pipes, 11, leading from the heating elements to the header, 6. In addition downcomers, 12, are provided 40 which connect the intermediate headers, 3, to the water header, 6.

In the part of the flue, C, adjoining the smoke-tube boiler, B, are arranged two high-pressure superheaters, 13 and 14. In this 45 part of the flue, C, there are only transverse connecting tubes, 15, between the intermediate containers, 3, but no other water tubes, the transverse tubes, 15, serving to protect the drum, 4, from the action of the hot 50 gases.

The high-pressure steam generated in the drum, 4, is led through the pipe, 16, provided with a shut-off valve to the superheater, 13, from which the pipe, 18, leads 55 the superheated steam to the interstage superheater, 19, arranged in the upper part of the smoke box. After traversing the heating elements, 20, of the interstage superheater, 19, the steam is led back through the pipe, 21, to the superheater, 14. Here 60 the high-pressure steam is re-superheated to a high temperature and passes through the pipe, 22, to the high-pressure cylinders, 23, of the locomotive. The exhaust steam from 65 the high-pressure cylinders flows through

the pipe, 24, to the interstage superheater, 19, to which in addition is connected the pipe, 26, coming from the steam space, 25, of the smoke-tube boiler, B.

The smoke-tube boiler, B, serves in general 70 as a feed-water heater for the high-pressure drum, 4, any low-pressure steam generated in the boiler, B, being mixed in the interstage superheater, 19, with the exhaust from the high-pressure cylinders.

The interstage steam, highly heated by the highly-superheated high-pressure steam, passes through the pipe, 28, to the low-pressure cylinders, 29, the exhaust from which is led in the usual way to the blast 80 pipe, 30.

Steam for the auxiliaries can be taken 85 through the pipe, 31, connected to the interstage superheater, 19.

The locomotive shown in longitudinal section in Fig. 4, is structurally similar as regards its main features to that shown in Figures 1 to 3, corresponding parts being indicated by the same reference symbols.

As regards the superheating arrangements, however, the essential difference lies 90 in the fact that the two superheaters, 32 and 33, in which the high-pressure steam is highly superheated first before admission to the heating elements of the interstage 95 superheater and then a second time before admission to the high-pressure stage of the engine, lie in the smoke tubes, 34, of the smoke-tube feed-water heater. The tubes of these superheaters project for a considerable 100 part of their length into the flue, C, so that in this way a sufficient superheating of the high-pressure steam is secured. Those parts of the superheater tubes lying in the flue, C, are protected against burning by the water 105 tubes, 8, which are distributed over the cross-section of the flue, C, as shown in Figure 2.

The high-pressure steam generated in the high-pressure drum, 4, is led through the pipe, 35, provided with a shut-off valve to the superheater, 32, from which the pipe, 36, leads the superheated steam to the interstage superheater in the smoke box. The superheated steam traverses the heating elements, 39, of the interstage superheater and is then led back through the pipe, 40, to the second superheater, 33, whence after being 110 again superheated, it flows through the pipe, 41, to the high-pressure cylinders, 23, of the engine. The exhaust from the high-pressure cylinders flows through the pipe, 42, to the interstage superheater, 38, in order, it may be in conjunction with low-pressure steam coming from the smoke-tube 115 boiler through the pipe, 43, to be in turn highly heated by the superheated high-pressure steam. The superheated interstage steam flows out of the interstage superheater through the pipe, 44, to the low-pressure cylinders, 29, of the engine, the exhaust from 120

which passes through the pipe, 45, to the blast pipe, 30.

Steam for the auxiliaries can be taken from the pipe, 46, connected to the inter-stage superheater, 38.

5 What I claim is:

1. In a high-pressure locomotive having a multi-stage engine, the combination of a high-pressure boiler constituting the fire box, a smoke-tube-feed-water-heater lying in the flue of the high-pressure boiler, a fire gas channel leading from the fire box to the smoke tubes, a steam heated interstage superheater adapted to superheat the exhaust steam of the high-pressure stage of the engine, a superheater adapted to superheat the high-pressure-steam and delivering to said interstage superheater, a second superheater adapted to re-superheat the high-pressure steam coming from the heating elements of the interstage superheater, the first mentioned superheater being located to receive heat from the fire gas channel, and water tubes of the high-pressure boiler distributed over the cross section of said channel and arranged in front of this superheater as a protection against the radiant heat of the furnace.

2. In a high-pressure locomotive having a multi-stage engine, the combination of a high-pressure boiler constituting the fire box, a smoke-tube-feed-water-heater lying in the flue of the high-pressure boiler, a fire gas channel leading from the fire box to the smoke tubes, a steam heated interstage superheater adapted to superheat the exhaust steam of the high-pressure stage of the engine, a superheater adapted to superheat the high-pressure-steam and delivering to said interstage superheater, a second superheater adapted to resuperheat the high-pressure steam coming from the heating elements of the interstage superheater, the first mentioned superheater being located to receive heat from said fire gas channel, water-tubes of the high-pressure boiler distributed over the cross section of said channel and arranged in front of the high-pressure superheaters as a protection against the radiant heat of the furnace, and a conduit adapted to lead steam developed in the smoke-tube-feed-water-heater to the interstage superheater.

3. In a high-pressure locomotive having a multistage engine, the combination of a high-pressure boiler constituting the fire box, a smoke-tube feed-water-heater lying in the flue of the high-pressure boiler, a fire gas channel leading from the fire box to the smoke tubes, a steam heated interstage superheater adapted to superheat the exhaust steam of the high-pressure stage of the engine, a superheater adapted to superheat the high-pressure-steam passing through the heating elements of the inter-

stage superheater, a second superheater adapted to resuperheat the high-pressure-steam coming from the heating elements of the interstage superheater, the high pressure superheater and the resuperheater being disposed in said fire gas channel, and water tubes of the high pressure boiler extending across the cross-section of said channel at points between the fire-box and said superheaters for the high pressure steam to protect said superheaters against the radiant heat of the furnace.

4. The combination as claimed in claim 3 wherein the first mentioned high pressure steam superheater is situated in the fire gas channel at a point between the resuperheater and the water tubes which extend across the cross-section of said channel.

In testimony whereof I have affixed my signature.

OTTO H. HARTMANN.
